UNITED STATES PATENT OFFICE.

GEORGE S. STUART, OF WASHINGTON, DISTRICT OF COLUMBIA.

AUTOMATICALLY-PROPELLED DEVICE.

1,320,348.

Specification of Letters Patent.

Patented Oct. 28, 1919.

Application filed February 5, 1919. Serial No. 275,142.

To all whom it may concern:

Be it known that I, GEORGE S. STUART, a citizen of the United States, residing at Washington, in the District of Columbia, have invented certain new and useful Improvements in Automatically-Propelled Devices; and I do hereby declare the following to be a full, clear, and exact description of the invention, such as will enable others skilled in the art to which it appertains to make and use the same.

My present invention relates to improvements in automatically propelled devices, wherein the device is intended to be automatically propelled by means of the mechanism which will be hereinafter more fully described.

The invention is more especially adapted for use in automatically propelled toys.

My invention will be more fully understood after reference to the accompanying drawings, in which like parts are indicated by similar reference symbols throughout the several views, and in which:—

Figure 1 shows a side elevation of one form of apparatus constructed according to my invention, in which the operating chambers are in elevation in the similitude of a fish.

Fig. 2 is a front view of the apparatus shown in Fig. 1.

Fig. 3 is a plan view of the device shown in Figs. 1 and 2.

Fig. 4 shows a section along the line 4—4 of Fig. 3, and looking in the direction of the arrows.

Fig. 5 is a detail view showing the driving wheel in section.

Fig. 6 is a perspective view of two of the buckets of the driving wheel shown in Fig. 5, parts being shown on a larger scale.

Fig. 7 is a similar view to Fig. 1, but shows a modification in which the contour of the operating chamber is in the similitude of a bird.

Fig. 8 is a similar view to Figs. 1 and 7, but shows the contour of the operating chamber in the similitude of a battleship; and

Fig. 9 is a similar view to Figs. 1, 7 and 8, but shows the operating chamber in the similitude of a horse, but with the various details shown in the other figures omitted.

The various details of the invention are more fully shown in Figs. 1 to 6 which will 55 be now described.

There are two operating chambers A each in side elevation in the form of a fish as shown, and these chambers are connected together in any convenient way as by means 60 of the wing surfaces B and B', which terminate in the upper and lower wings B² and B³, respectively, projecting laterally from the chambers A, which wings are connected together in any convenient way as by the 65 braces b.

Beneath the lower plane are the brackets C and D, in which are journaled the front wheels C' and the rear wheel D'. The rear wheel D' may be swiveled if desired, as is 70 well known in the art, but the bracket D is shown as attached to the lower plane B'.

Each main chamber A is provided with an air chamber A° therein, which is closed at the top as by means of the partitions a°, 75 a² and a³, there being a passage for air through the main chamber from the front opening a to the rear opening a'.

I may provide auxiliary side chambers A⁴ connected with the main chamber by means 80 of the passage a⁶.

Mounted in the chamber A° beneath the curved partitions a² and a³, respectively, are the drive wheel E and the auxiliary wheel F, which are rotated in the same direction by means of a belt or sprocket chain G, the driving wheels E being mounted on the shaft H driven by any suitable source of power, such as the engine I. In place of the engine a suitable coil spring or rubber band 90 may be used, as will be hereinafter described with reference to Figs. 7 to 9.

The preferred construction of the drive wheel E is shown in Figs. 5 and 6, in which e are buckets attached to the spokes of the wheel and which are stiffened by the braces e'. In order to secure a snug fit, these buckets are preferably provided with a strip of rubber or leather e² as shown in Fig. 6.

In order to regulate the supply of fluid 100 drawn in through the front opening a I provide a suitable regulating device, such as the bellows attachment J shown in Figs. 1 and 2, which may be raised or lowered by means of the cord K passing over the pulley 105 k and wound upon the wheel L. By turn-

ing this wheel L both of the lower jaws of the mouths of the two fishes may be raised or lowered, thus adjusting the opening for fluid through the mouth of the fish. In 5 a similar way the passage of fluid through the passages a^4 in the side chambers A ^{4} may be controlled by means of gate valves M connected by the links m to the crank arms m' on the shaft m ^{2} , which shaft may be rotated 10 by means of the hand lever N.

The operating chambers A are shown as provided with fins O, O' and O ^{2} which serve to increase the similitude of the apparatus to a fish, and these fins also serve to steer 15 the apparatus in a straight direction.

I have shown as attached to the tails of the two fishes a rudder attachment comprising vertical or steering rudders P and horizontal rudders P'. These rudders swing 20 about the rudder posts P ^{2} and may be operated simultaneously by means of the crank arms Q, the links q, the double lever Q' and the rope or chain q' passing over the steer wheel Q ^{2} , as shown most clearly in Fig. 3.

25 In the form of device shown in Fig. 7, the general arrangement is the same as in Figs. 1 to 6, except that I show the side elevation of the operating chambers in the form of a bird, and instead of the bellows attachment J I show a hinged door J'; otherwise the construction of the parts is substantially the same as in the before described figures.

In the form of device shown in Fig. 8, 30 the side elevation of the operating chamber resembles a battleship, and the air passage through the operating chamber is controlled by means of a hinged door J ^{2} .

In the form of device shown in Fig. 9, the operating chamber is shown in the similitude of a horse, and any means for regulating 40 the influx of air into the operating chamber are omitted.

In the forms of device shown in Figs. 7, 8 and 9 instead of the engine I, shown in 45 Figs. 1 to 3, any suitable means for rotating the drive shaft may be used, such as the spring I' indicated in dotted lines in Figs. 7 and 8, or the rubber band I ^{2} indicated in dotted lines in Fig. 9.

50 The operation of the device is as follows:—

Referring first to Figs. 1 to 3, suppose the device to be used on land, and suppose the means for rotating the drive shaft H to be 55 set in operation, the drive wheel E will force air through the air passage in the lower part of the operating chamber, sucking the air in from the front and ejecting the same at the rear. The auxiliary wheel F will prevent 60 air from being carried around in the upper part of the chamber A ^{o} and will tend to cause the air to be ejected directly to the rear; the resultant effect will be that the device will be propelled forward. The speed 65 of the propulsion will be determined by the

speed of the drive wheel E, and the size of the air openings a and a ^{4} , which openings are controlled by the bellows attachment J and the gate valves M.

If the rudders be turned to the right or 70 left, the device will tend to swerve in the same direction. The fins will tend to keep the device upright, especially if the lower fins O' and O ^{2} are ballasted as already described. 75

If the device is run from land into the water, water will be sucked in through the openings a and a ^{4} and will be ejected rearward, thus causing the device to move rapidly through the water; the drive wheel E in that case serving as an ordinary paddle wheel, and the buoyancy of the air in the upper portion of the chamber A ^{o} will serve to keep the device afloat. Moreover, the inclined planes will tend to lift the device in 80 the water. 85

In the forms of the device shown in Fig. 7 the apparatus is equally capable of being used on land or in the water.

The simplified modification shown in Fig. 9 is intended primarily for use on land only, but it may be also operated in the water. In this form, however, no wing attachments are shown. 90

With any of the forms of the device, the apparatus is adapted when started to run over smooth ground or a smooth platform, or to swim in the water. 95

It will be obvious that various modifications of the herein described apparatus and various changes in the combination and arrangement of parts might be made without departing from the spirit of my invention; and I do not mean to limit my invention to precise details of construction except as particularly pointed out in the claims. 100

Having thus described my invention what I claim and desire to secure by Letters Patent of the United States is:— 110

1. An automobile device of the character described, comprising an operating chamber provided with a passage for fluid extending through the lower portion thereof, a drive wheel provided with buckets dipping down into said passage, means for rotating said drive wheel, an auxiliary wheel located in rear of said drive wheel and also provided with buckets, and means for rotating said auxiliary wheel in the same direction as said drive wheel, substantially as described. 115

2. An automobile device of the character described, comprising an operating chamber provided with a passage for fluid extending through the lower portion thereof, a drive wheel provided with buckets dipping down into said passage, means for rotating said drive wheel, an auxiliary wheel located in rear of said drive wheel and also provided with buckets, and means for rotating said 120 125 130

auxiliary wheel in the same direction as said drive wheel, with means for varying the cross section of said fluid passage in front of said drive wheel, substantially as described.

3. An automobile device of the character described, comprising an operating chamber provided with a passage for fluid extending through the lower portion thereof, wheels supporting said chamber, a drive wheel provided with buckets dipping down into said passage, means for rotating said drive wheel, an auxiliary wheel located in rear of said drive wheel and also provided with buckets, and means for rotating said auxiliary wheel in the same direction as said drive wheel, substantially as described.

4. An automobile device of the character described, comprising an operating chamber provided with a passage for fluid extending through the lower portion thereof, wheels supporting said chamber, a drive wheel provided with buckets dipping down into said passage, means for rotating said drive wheel, an auxiliary wheel located in rear of said drive wheel and also provided with buckets, and means for rotating said auxiliary wheel in the same direction as said drive wheel, with means for varying the cross section of said fluid passage in front of said drive wheel, substantially as described.

5. An automobile device of the character described, comprising a frame mounted on wheels, a pair of operating chambers each provided with a passage for fluid extending through the lower portion thereof, mounted on said frame, a drive wheel in each operating chamber provided with buckets dipping down into said passage, means for rotating said drive wheels, an auxiliary wheel located in rear of each of said drive wheels and also provided with buckets, and means for rotating said auxiliary wheels in the same direction as said drive wheels, substantially as described.

6. An automobile device of the character described, comprising a frame mounted on wheels, a pair of operating chambers each provided with a passage for fluid extending through the lower portion thereof, mounted on said frame, a drive wheel in each operating chamber provided with buckets dipping down into said passage, means for rotating said drive wheel, an auxiliary wheel located in rear of said drive wheel and also provided with buckets, and means for rotating said auxiliary wheels in the same direction as said drive wheels, with means for varying the cross section of said fluid passage in front of said drive wheel, substantially as described.

7. An automobile device of the character described, comprising a frame mounted on wheels, a pair of operating chambers each provided with a passage for fluid extending

through the lower portion thereof, mounted on said frame, wings projecting laterally from said chambers, a drive wheel in each operating chamber provided with buckets dipping down into said passage, means for rotating said drive wheels, an auxiliary wheel located in rear of each of said drive wheels and also provided with buckets, and means for rotating said auxiliary wheels in the same direction as said drive wheels, substantially as described.

8. An automobile device of the character described, comprising a frame mounted on wheels, a pair of operating chambers each provided with a passage for fluid extending through the lower portion thereof, mounted on said frame, wings projecting laterally from said chambers, a drive wheel in each operating chamber provided with buckets dipping down into said passage, means for rotating said drive wheels, an auxiliary wheel located in rear of each of said drive wheels and also provided with buckets, and means for rotating said auxiliary wheels in the same direction as said drive wheels, with means for varying the cross section of said fluid passages in front of said drive wheels, substantially as described.

9. An automobile device of the character described, comprising an operating chamber provided with a passage for fluid extending through the lower portion thereof, wheels supporting said chamber, wings projecting laterally from said chamber and set at an incline, a drive wheel provided with buckets dipping down into said passage, means for rotating said drive wheel, an auxiliary wheel located in rear of said drive wheel and also provided with buckets, and means for rotating said auxiliary wheel in the same direction as said drive wheel, substantially as described.

10. An automobile device of the character described, comprising an operating chamber provided with a passage for fluid extending through the lower portion thereof, wheels supporting said chamber, wings projecting laterally from said chamber and set at an incline, a drive wheel provided with buckets dipping down into said passage, means for rotating said drive wheel, an auxiliary wheel located in rear of said drive wheel and also provided with buckets, and means for rotating said auxiliary wheel in the same direction as said drive wheel, with means for varying the cross section of said fluid passage in front of said drive wheel, substantially as described.

11. An automobile device of the character described, comprising a frame mounted on wheels, a pair of operating chambers each provided with a main passage for fluid extending through the lower portion thereof, mounted on said frame, auxiliary chambers each provided with fluid passages connected

- to said main fluid passage, a drive wheel in each operating chamber provided with buckets dipping down into said passage, means for rotating said drive wheels, an auxiliary wheel located in rear of said drive wheel in each chamber and also provided with buckets, and means for rotating said auxiliary wheels in the same direction as said drive wheels, substantially as described.
- 10 12. An automobile device of the character described, comprising a frame mounted on wheels, a pair of operating chambers each provided with a main passage for fluid extending through the lower portion thereof, 15 mounted on said frame, auxiliary chambers each provided with fluid passages connected to said main fluid passage, a drive wheel in each operating chamber provided with buckets dipping down into said passage, 20 means for rotating said drive wheel, an auxiliary wheel located in rear of said drive

wheels in each chamber and also provided with buckets, and means for rotating each of said auxiliary wheels in the same direction as said drive wheels, with means for varying 25 the cross section of said fluid passage in front of said drive wheels, substantially as described.

13. An automobile device of the character described, comprising an operating chamber 30 provided with an air passage beneath the same, a drive wheel mounted in said operating chamber and provided with buckets dipping down into said passage, means for rotating said drive wheel, an auxiliary 35 wheel also mounted in said operating chamber in rear of said drive wheel and also provided with buckets, and means for rotating said auxiliary wheel in the same direction as said drive wheel, substantially as de- 40 scribed.

GEORGE S. STUART.
